UNITED STATES PATENT OFFICE.

EDWIN S. CARMAN AND EARL F. OYSTER, OF CLEVELAND, OHIO, ASSIGNEES TO THE CLEVELAND OSBORN MANUFACTURING COMPANY, OF CLEVELAND, OHIO, A CORPORATION OF OHIO.

AUTOMATIC CUT-OFF FOR AIR JOLT-MACHINES.

1,379,799.

Specification of Letters Patent. Patented May 31, 1921.

Application filed March 17, 1919. Serial No. 283,148.

To all whom it may concern:

Be it known that we, EDWIN S. CARMAN and EARL F. OYSTER, citizens the United States, and residents of Cleveland, county 5 of Cuyahoga, State of Ohio, have jointly invented a new and useful Improvement in Automatic Cut-Offs for Air Jolt-Machines, of which the following is a specification, the principle of the invention being herein explained and the best mode in which we have 10 contemplated applying that principle, so as to distinguish it from other inventions.

The present invention, relating, as indicated, to an automatic cut-off for air-jolt machines, is intended for use with a molding machines of the well-known jolting type in which the mold is jolted by a pressure fluid actuated piston and cylinder. One of the main objects of the invention is 15 to provide a device which may be set to automatically cut out the cylinder of the jolt machine after a predetermined number of jolts, and to accomplish this by the use of the same pressure fluid which is connected to the jolt machine for the operation 20 of the jolting mechanism. A further object of the invention is the provision of such a device which may be conveniently operated and which will effect a rapid valve closure 25 and shut off the pressure fluid. To the accomplishment of the foregoing and related ends, said invention, then, consists of the means hereinafter fully described and particularly pointed out in the claims.

30 The annexed drawing and the following description set forth in detail certain mechanism embodying the invention, such disclosed means constituting, however, but one of various mechanical forms in which the 35 principle of the invention may be used.

In said annexed drawings:—

Figure 1 is a perspective view, illustrating the standard type of jolting machine with our improved cut-out in operative connection therewith; Fig. 2 is a plan view of the cut-off mechanism with certain parts thereof in section; Fig. 3 is a central vertical section through the device of Fig. 2 taken on the line 3—3 of Fig. 2; Fig. 4 is 45 a similar partial section with certain parts in elevation taken on the line 4—4, Fig. 2; Fig. 5 is a section on the line 5—5, Fig. 3, showing the relative positions of the valve controlling members when the valve is in

closed position; Fig. 6 is a section on the 55 line 6—6, Fig. 3, showing the air valve in the closed position corresponding to the positions of the valve-controlling parts of Fig. 5; Fig. 7 is a plan view similar to Fig. 2, but showing the indicating dial in a different position; Fig. 8 is a section similar to Fig. 5, but showing the valve-controlling parts in the positions corresponding to the position of the indicating dial of Fig. 7; Fig. 9 is a plan view similar to Figs. 2 and 65 7, but showing the device in a position ready to operate; Fig. 10 is a section similar to Figs. 5 and 8, but showing the valve-controlling parts in positions corresponding to the position of the indicator dial in Fig. 70 9; Fig. 11 is a horizontal section showing the position of the escapement mechanism when the device is in operative position; and Fig. 12 is a view in perspective of the 75 air valve operating element.

The operation of air jolt machines is usually controlled by an operator, who turns on the air, admitting the air to the jolting cylinder, from which it is automatically discharged, the operator permitting this operation to continue until he thinks that the mold is properly jolted. This involves a close personal watch by the operator on the character of the mold and on the type and particular condition of the sand in each 80 jolting operation, and as it is too much to expect that the ordinary operator will carefully and always properly analyze these conditions, the result is a certain lack of uniformity in the condition of the molds after 85 jolting, with the result either that an insufficient jolting action is obtained or a waste of time. The present device is designed to be set to allow a predetermined number of vibrations or joltings only, followed by the 90 automatic rapid shut-off of the pressure-fluid, and when once the proper number of vibrations has been determined for any particular conditions, this exact number can be given to each mold by means of our device. 95

In Fig. 1 there is shown a standard type of jolting machine, consisting of a base or frame which carries a reciprocating mold-receiving table 2, supported and operated by means of a fluid pressure cylinder 3, the 100 table of course being connected to the piston in the cylinder. Valve-operating mechanism for the admission and escape of the 105

fluid pressure from the cylinder 3 is carried in a suitable valve chamber 4 mounted at the side of the jolting cylinder, and this valve-controlling mechanism may conveniently take the form of an auxiliary piston valve or other means. Fluid pressure is admitted to the valve chamber 4 by means of a conduit 7, and is discharged from the cylinder 3 in the usual manner when the 10 table is dropped after leaving.

Our improved automatic cut-off is connected to the fluid pressure admission line 7, and is shown at the right in Fig. 1. The device is in the form of a cylindrical casing, 15 having inlet and exhaust ports 9 and 10, respectively, for the connection thereto of the two ports of the fluid pressure conduit 7, these ports being shown in Fig. 3. The ports are controlled by means of a valve 11 20 (see Figs. 3 and 4), which valve is provided with a partially circumferentially connecting passage 12 for connecting or disconnecting the inlet or exhaust ports 9 and 10, as will be readily understood from an inspection of these two figures. This valve is maintained in close connection with the ports by means of a spring 13 mounted between a cap 14, carried on the lower part of the cylindrical casing, and is operated by 25 means of a removable L-shaped valve stem 15, which extends through the portion of the casing in which are formed the ports 9 and 10, the lower portion 15a of the stem engaging in a recess in the valve and the upper 30 part being journaled in the casing. Above this portion of the casing just referred to, the valve stem 15 terminates and is fastened to a valve-operated hand or member 16.

Easily adjustable means are provided for 40 operating the valve operated member or hand 16, such means being carried in the upper part of the cylindrical casing 17 of the device, and the setting mechanism being mounted on top of the chamber proper.

45 This valve-setting means includes two hands or lugs 18 and 19, respectively, fixed to a shaft 20 and a sleeve 21, rotatably mounted about the shaft. The shaft 20 is in alinement with the shaft or valve stem 15 and extends upwardly through the top of the chamber where it carries an indicating dial 22 keyed thereto. This indicating dial is graduated about its circumference, as shown in Fig. 9, and bears numerals adjacent to the respective graduations, which indicate the number of blows that will be delivered by the jolting machine before the operation of the cut-off upon various settings of this indicating member. The sleeve 50 21 carries externally of the casing an operating lever or handle 23, which, in the closed position of the valve 11, is in contact with a stop 24 formed on an encircling ring 25, formed as a part of the cylindrical casing. 55 A lock nut 26 is threaded on the extending

end of the shaft 20 and may be turned down to clamp the indicating dial 22 to the handle 23, in this way clamping together the shaft 20 and sleeve 21, and operating in unison the two valve-controlling hands or lugs 18 70 and 19.

Before describing the operation of the dial and valve operating means, the actuating mechanism for closing the valve and cutting off the supply of fluid pressure through the 75 conduit 7, should be described. On the sleeve 21 is carried a coiled spring 30, the outer end of which is attached to the casing at the point 32, (see Fig. 2), and this spring serves to return the sleeve and handle 23 to 80 their normal position against the stop 24 upon the release of the mechanism now to be described, and at the same time the spring serves to return the valve 11 to its closed position, as will presently be described. 85

Also keyed to the sleeve 21 are two ratchet disks 33 and 34, which are shown in plan in Fig. 11 and which are respectively engaged by two pawls 35 and 36, (Figs. 2 and 11). The two pawls are pivoted about fixed axes 90 and have their other ends engaged with a stem 37 extending from a piston 38 in a cylinder 39, which is formed as a separate casing, removably attached to the side of the main casing 17. The piston 38, operating in the cylinder 39 is actuated by means of fluid pressure carried thereto by means of a conduit 40, extending to the valve chamber 4 of the jolt machine and entering the cylinder through a port 41. Fluid pressure 95 is thus admitted through this conduit 40, through the cylinder 39, upon each admission of fluid pressure to the cylinder 3 of the jolt machine, and is simultaneously discharged through the same conduit, when 100 the fluid pressure is discharged from the cylinder 3 of the machine so that there is an actuation inward of the piston 38 upon each reciprocation of the table of the machine. This piston 38 is normally pressed 105 outward by means of a spring 42. The extending stem 37 of the piston is recessed to receive loosely therein a re-bent end 44 of the pawl 35, which is connected, by means of the spring 46, with the rear end of the 110 pawl 36 which abuts against the end of the stem 37. Thus upon inward movement of the piston 38 the engaging end of the pawl 35 is pressed inward and the engaging end of the pawl 36 is forced out of the toothed 115 disk 33 by the rotation of this disk under the influence of the spring 30, and by the pressure of the stem 37 against the other end of this pawl. Similarly, upon the retraction of the piston 38, the pawl 35 is disengaged from its ratchet wheel, and the pawl 36 is pulled into engagement with its ratchet 33 by the spring 46 so that there is a step-by-step or escapement movement of the ratchet wheels 33 and 34 under the in- 120 125 130

termidiate engagement of the pawls 35 and 36 therewith. Movement of these two ratchet disks is effected by the coiled spring 30, but this movement is an escapement 5 movement and the ratchets are permitted to move the width of one tooth only upon each actuation of the piston 38, which in turn corresponds to each reciprocation of the cylinder of the jolt machine.

10 As the ratchet disks 33 and 34 are keyed to the sleeve 21, carrying the indicating dial 22, it will be understood that the graduations on the indicator dial represent the number of notches which must be released 15 one by one by the pawls to permit the return of the indicator dial to its normal position from any position at which it is preliminarily set. Thus, if the indicator dial is set at the numeral 25, as will be explained 20 more clearly presently, it will require 25 operations of the jolt machine and of the piston 38 to allow the spring 30 to return the disks to their normal positions, and thus to return the valve 11 to a closed position 25 upon operation of the jolt machine.

The valve-operating hand or lug 16 has a range of movement between its closed and open positions of the distance between the stops 50 and 51, the pin 51 defining the open 30 position of the valve, that is, when the lug 16 is in contact therewith, and the stop 50 defining the closed position. In the operation of the device, assuming that the valve is closed, and that the handle 23 is in a 35 position to contact the stop 24, then the nut 26 may be loosened and the indicator dial turned in a clockwise direction, (looking downward upon the device, in plan) until the desired number of jolts, as indicated by 40 figures on the dial, is opposite the central arrow 53 on the handle. For convenience in setting the dial a handle 54 is formed thereon. If 25 jolts are desired the numeral 25 is brought into alinement with the arrow 45 53 on the handle 23 and the nut 26 is then tightened to lock together the dial 22, the handle 24, the shaft 20 and the sleeve 21. This also locks together for simultaneous 50 operation the lugs 18 and 19 on the shaft 20 and sleeve 21, respectively. The rotation 55 of the dial in a clockwise direction, however, spaces the lug or hand 18 a considerable distance from the normal or closed position of the valve hand 16, as shown in Fig. 8, while the valve closing hand 19 is in contact with the valve hand 16, and the latter is in contact with the stop 50, so that the valve is then closed. The handle 24 is then 60 swung in a counter-clockwise direction, which causes the hand 18 to pick up the valve-operating hand 16 after a certain movement of the hand 18 sufficient to bring it into a position adjacent to the stop 50.

The valve is then swung into an open position by bringing the valve hand 16 into con-

tact with the stop 51, as shown in Fig. 10. At this time, the valve-closing hand 19 is spaced a considerable distance from the valve hand 16. As soon as the valve is opened air is admitted to the jolt machine 70 and also to the cylinder 37, causing a step-by-step actuation of the escapement mechanism. There is no other operation, and the position of the valve is not changed until the closing hand 19 has been turned sufficiently to contact with the valve-operating hand 16 in its position against the stop 51. When this position is reached two blank spaces 55 are reached on the periphery of the ratchet disks 33 and 34 so that the pawls 80 35 and 36 ride on these blank spaces and permit the spring 30 to suddenly swing the valve shut by the engagement of the valve-closing hand 19 against the valve-operating hand 16. The blank spaces on the ratchet 85 disks 33 and 34 extend over the same angle as the angular distance between the stops 50 and 51, so that as soon as these blank spaces on the ratchet disks are reached the further movement of the mechanism will 90 be rapid, and the closing of the valve will be practically instantaneous. It will be understood that the blank spaces on the two ratchet disks are formed in the same staggered relation as are the positions of the 95 engaging ends of the pawls 35 and 36, so that these pawls will cease to act at the same moment and permit a free return of the parts to a normal position and an immediate swinging shut of the valve 11. 100

Other modes of applying the principle of our invention may be employed instead of the one explained, change being made as regards the mechanism herein disclosed, provided the means stated by any of the following claims or the equivalent of such stated means be employed. 105

We therefore particularly point out and distinctly claim as our invention:—

1. The combination with pressure-fluid 110 actuated jolt-mechanism, of a valve controlling the supply of pressure-fluid thereto, means tending to close said valve, means for manually opening said valve, and an escapement adapted to regulate the closing 115 of said valve.

2. The combination with pressure-fluid actuated jolt-mechanism, of a valve controlling the supply of pressure-fluid thereto, means tending to close said valve, means 120 for manually opening said valve, and an escapement affected by the operation of said mechanism adapted to regulate the closing of said valve.

3. The combination with pressure-fluid 125 actuated jolt-mechanism, of a valve controlling the supply of pressure-fluid thereto, means tending to close said valve, means for manually opening said valve, and an escapement operable by the pressure-fluid 130

- from said mechanism adapted to regulate the closing of said valve.
4. The combination with pressure-fluid actuated jolt-mechanism, of a valve controlling the supply of pressure-fluid thereto, means tending to close said valve, means for manually opening said valve, and a manually adjustable escapement adapted to regulate the closing of said valve.
5. The combination with pressure-fluid actuated jolt-mechanism, of a valve controlling the supply of pressure-fluid thereto, means tending to close said valve, means for manually opening said valve, and a manually adjustable escapement affected by the operation of said mechanism adapted to regulate the closing of said valve.
6. The combination with pressure-fluid actuated jolt-mechanism, of a valve controlling the supply of pressure-fluid thereto, means tending to close said valve, means for manually opening said valve, and a manually adjustable escapement operable by pressure-fluid from said mechanism adapted to regulate the closing of said valve.
7. The combination with pressure-fluid actuated jolt-mechanism, of a valve controlling the supply of pressure-fluid thereto, resilient means tending to close said valve, and an escapement operable by the pressure fluid from said mechanism adapted to regulate the closing of said valve.
8. The combination with pressure-fluid actuated jolt-mechanism, of a valve controlling the supply of pressure-fluid thereto, resilient means tending to close said valve, and an escapement mechanism operable by the pressure-fluid from said mechanism, and adapted to instantaneously close said valve after a predetermined cycle of operation of said jolt-mechanism.
9. The combination with pressure-fluid actuated jolt-mechanism, of a valve controlling the supply of pressure-fluid thereto, resilient means tending to close said valve, a closing member for said valve, an opening member adjustable with respect to said closing member, and an escapement regulated by the initial adjustment of said opening member, said escapement being operable by the pressure-fluid from said mechanism and being adapted to regulate the closing of said valve.
10. The combination with pressure-fluid actuated jolt-mechanism, of a valve controlling the supply of pressure-fluid thereto, resilient means tending to close said valve, separate opening and closing members for said valve adjustable with respect to each other to vary the position of said closing member in the open position of said valve, an indicator dial connected to said members, and an escapement operable by the pressure-fluid from said mechanism to regulate the closing of said valve, said es-

capement in turn being regulated by the initial adjustment of said indicator dial and said opening and closing members.

11. The combination with pressure-fluid actuated jolt-mechanism, of a valve controlling the supply of pressure-fluid thereto, means tending to close said valve, an escapement including a pawl and ratchet adapted to regulate the closing of said valve, said escapement being operable by the pressure-fluid from said mechanism, and means adapted to effect operation of said escapement to allow closing of said valve after a predetermined number of cycles of operation of said mechanism. 80

12. The combination with pressure-fluid actuated jolt-mechanism, of a valve controlling the supply of pressure-fluid thereto, means tending to close said valve, an escapement operable by the pressure-fluid from said mechanism, said escapement regulating closing of said valve and being adjustable to release said valve closing means upon a predetermined number of cycles of operation of said mechanism. 90

13. The combination with pressure-fluid actuated jolt-mechanism, of a valve controlling the supply of pressure-fluid thereto, means tending to close said valve instantly when released, an adjustable escapement operable by pressure-fluid to release said valve closing means and permit an instant closing thereof, and means adapted to preliminarily set said escapement to release said valve closing means after a predetermined number of cycles of operation of said mechanism. 95

14. The combination with pressure-fluid actuated jolt-mechanism, of a valve controlling the supply of pressure-fluid thereto, means tending to close said valve instantly when released, an adjustable escapement operable by pressure-fluid to release said valve closing means and permit an instant closing thereof, and means including an adjustable indicator dial adapted to preliminarily set said escapement to release said valve closing means after a predetermined number of cycles of operation. 105

15. In a device of the character described, the combination of a casing having a pressure-fluid passage therethrough, and a valve controlling such passage, a second casing removably attached to said first-named casing, and means tending to close said valve, escapement means operable by pressure-fluid and adapted to regulate the operation of said valve closing means, said valve closing means and said escapement being wholly inclosed and carried in said second removable casing. 115

Signed by us, this 1st day of March, 1919.
